UNITED STATES PATENT OFFICE.

ROY ALEXANDER WEAGANT, OF ROSELLE, NEW JERSEY, ASSIGNOR, BY MESNE ASSIGNMENTS, TO RADIO CORPORATION OF AMERICA, A CORPORATION OF DELAWARE.

PROCESS AND APPARATUS FOR RECEIVING RADIOSIGNALS.

Application filed July 19, 1917. Serial No. 181,458.

To all whom it may concern:

Be it known that I, ROY ALEXANDER WEAGANT, a citizen of the United States, residing in the town of Roselle, in the county of Union, State of New Jersey, have discovered certain new and useful Improvements in Processes and Apparatus for Receiving Radiosignals, of which the following is a specification.

10 My invention comprises a new method for the reduction of interference with radio communication due to atmospheric disturbances variously known as "static," strays or "X's," and new apparatus for practicing the new method.

My invention, broadly considered, may be carried out by various arrangements of apparatus, those shown and described in the drawing accompanying and forming a part 20 of this specification being the preferred forms of apparatus.

Referring to the drawing,

Figure 1 is a schematic diagram illustrating receiving apparatus embodying my invention, and adapted for use in practicing 25 my improved process.

Figure 2 illustrates a modified arrangement, in which an alternative form of antenna is employed, and in which a different 30 arrangement of adjusting devices is used. As an additional feature, it includes a coupling neutralizing means.

Figure 3 shows the preferred disposition or relation of the receiving apparatus to the 35 transmitting apparatus.

In the investigation of static disturbances, I have discovered that antennæ separated from one another by considerable distances appear to be acted upon by such disturbances 40 substantially simultaneously, the effect being as though such disturbances were caused by electro-magnetic waves or impulses propagated perpendicularly to the surface of the earth, and almost without 45 horizontal components. The effect, in other words, is as though these disturbances chiefly originated at a great height above the earth and had their horizontal components substantially neutralized, so that widely 50 separate antennæ, if on the same level, have disturbances set up in them which occur simultaneously.

I have reached this conclusion after numerous tests which appear to admit of no

other explanation, but whether or not it is a 55 correct statement of the facts, I find that by proceeding on this assumption and using a directional combination of separated antennæ as hereinafter described, I am able to very largely overcome the interference with 60 reception caused by the most objectionable forms of atmospheric disturbances.

The disturbing causes do not behave as though possessed of either definite wave length or decrement, but set up in the antennæ oscillations which have the frequency and the decrement of the antennæ themselves, and by suitable adjustments, I find it possible to cause the electromotive forces, induced in two or more antennæ by the atmospheric disturbances, to set up currents therein of the same wave length, decrement, and phase, so that by opposing their effect on the detector circuit substantial neutralization 70 may be accomplished.

The effects produced upon two such antennæ by signals will, however, be out of phase with one another, except when the signal is received in a line at right angles to a plane common to the antennæ. This difference of phase will be greatest when the antennæ are in a common plane which also passes through the point of origin of the signals.

I have found that with such an arrangement it is possible to cause the effects produced in a plurality of antennæ to be so combined in a single circuit as to neutralize or combine differentially the effects due to static and those due to signals coming in a 85 direction at right angles to the plane of the antennæ, while combining cumulatively the effects of signals arriving in the common plane of the antennæ, or from directions not too nearly at right angles thereto.

The difference in phase of the electromotive forces set up by received signal waves will also depend upon the distance of separation of the effective centers of the antennæ measured in the direction of propagation of the waves.

In my own practice of the invention up to this time, I have found it desirable to bring leading-in wires from the antennæ to a common point, preferably, but not necessarily, 105 to the center of the antenna system. If antennæ of the ordinary open circuit type are employed, these leading-in wires act as part

of the antennæ in the absorption of energy from the signal waves, and thus the effective separation of the antennæ becomes less than the actual separation of the elevated conductors. I have found that this disadvantage can be overcome by employing antennæ in the form of vertical loops. I have found that a vertical loop antenna, without earth connection, will have electromotive forces set up in it as a result of atmospheric disturbances, which appear to depend, for a given horizontal dimension, upon the mean vertical separation of the horizontal portions of the loop from one another. For example, if the loop is in the form of a rectangle having two of its sides horizontal, the magnitude of the effective electromotive forces set up appears to depend upon the vertical separation of the two horizontal sides.

On the other hand, the effect of a received signal on a single vertical loop antenna depends upon the direction from which the signal is received, and, for a given vertical dimension, upon the distance between the vertical sides.

The maximum effect for a given antenna is obtained when the plane of the antenna passes through the point of origin of the signal to be received, since the effective electromotive force in such a loop depends upon the difference in phase of the effects in the two vertical sides of the antenna.

I have found that it is possible to take advantage of these facts to substantially eliminate the above-mentioned effects of the leads, and secure an effective separation equal to the distance between the centers of the loops, if the two leading-in wires from each of two such loops antennæ are similarly situated with respect to earth, as for example, by being carried on poles at the same height above earth, so that the effects upon the leads, both of atmospheric disturbance and of signal waves, will be neutralized. This is because the plane containing the leads is at right angles to the vertical oscillator from which the signals originate and no current is produced in them by said signal so long as its wave front is vertical. My tests have shown, also, that these horizontal leads do not have currents set up in them by static disturbances at all comparable to those set up in the antennæ.

By employing two such antennæ and conducting the leading-in wires to a common point, advantageously, but not necessarily equidistant from the two, I am able, by combining the actions on the two loop antennæ in a single instrument or group of instruments, to oppose the effects of static upon the two antennæ, and thereby neutralize them, while combining cumulatively the effects of the signal, obtaining the full benefit of the separation of the antennæ without

any loss of effective separation, due to the action of the leads.

By applying this method I have succeeded in receiving commercially readable transatlantic signals through atmospheric disturbances so powerful and continuous as to make it otherwise impossible even to recognize the existence of the desired signal.

Referring to the arrangement shown in Figures 1 and 3 of the drawings, A A' represent two loop antennæ, preferably in the same plane with one another, and with the transmitting station T from which the desired signals are to be received, as shown in Figure 3, but it is not essential that this condition should be absolutely attained. Two pairs of leads B B' extend from said antennæ to a receiving station which may advantageously, but need not necessarily be located midway between the two antennæ. These leads are preferably supported on poles, as shown in Figure 3, and should preferably be kept at the same distance from the earth as above noted, and the separation of the wires of each pair from each other may advantageously be the same.

Each of the leads B and B' has included therein, preferably but not essentially, in each wire thereof, suitable tuning inductances C C' from which connections, including variable capacity elements, lead to any suitable apparatus in which the effects may be combined as above described. That shown comprises pairs of coils D D' to which the connections from coils C C' are led, the circuit being completed in each case by a variable condenser indicated at E E'. It will be noted that this gives a symmetrical arrangement, and this I have found desirable for best results, but not essential to good results.

Instead of a single condenser for each antennæ circuit located as shown, it may be located anywhere else in the lead wires, or two condensers may be employed, one in each lead. A symmetrical arrangement seems to give the best results.

The coils of each pair D D' may be adjustable as to their separation, but they also operate well when wound together. The coils may be circular or rectangular or other form.

Within the space affected by coils D D', and preferably rotatably mounted on an axis parallel to the planes of coils D D', is a coil F which in operation is subjected to the fields of force set up in the coils D D', and which is suitably connected to the detecting and indicating circuits. By suitably connecting the coils and adjusting the angular position of the coil F, the effects due to the static disturbances neutralize or are combined differentially in the coil F, while the effects due to the signals combine to produce a resultant current therein. In this

manner a nearly complete elimination of the most objectionable types of static disturbances is possible.

The electromotive forces produced in the two antennæ by the static disturbances appear to be as pointed out, substantially in phase, and by suitable adjustments of the constants of the circuit, the currents are also in phase. Their effect in the coils D D' is, therefore, to produce a magnetic field having substantially a fixed direction. The effects of the received signal being to set up currents differing in phase, these currents flowing in the coils D D' will produce either a resultant rotating magnetic field or a stationary magnetic field at right angles to that produced by the static disturbances according to the phase difference between said currents. By locating the coil F in the plane of the magnetic field due to the static disturbances, the effect of the static disturbances will be neutralized upon the coil F, while a resultant effect is produced by the desired signal. By rotating the coil F in this arrangement, so that it passes from the position where its plane is parallel to that of the field due to the interfering disturbances to one at right angles therefrom, the interference will pass from a minimum to a maximum effect, since in the latter position the interfering disturbances would cumulatively affect the coil F.

If the difference in phase of the currents produced by the desired signals is not 180°, then the position of the coil F, which gives maximum signal, will not, with this arrangement, be that of minimum interference, but the position of minimum interference will still give a large percentage of the maximum attainable signal strength.

The separation of the antennæ A A' measured from center to center of the loops, may be anything desired within considerable limits, so long as it be sufficient so that the difference in phase between the resultant electromotive force is appreciable and adequate to give a resultant magnetic (or electro-static) field, utilizable to create detectable signal currents, without requiring an impracticable degree of refinement of construction or manipulation. The preferable separation is one-half of a wave length, since this results in currents due to the desired signals exactly opposite in phase, whereby, if the circuits are so arranged as to cause the effects of static to oppose, the signal effects will be added to produce a stationary magnetic field, alternating in polarity, to act upon the coil F of the local circuit. If the separation be less than one-half of the wave length, the effects will be combined geometrically to form a resultant rotating field, which will be substantially uniform, if the separation is one quarter of the wave length, but will be a so-called elliptical field

if the separation is something different from one-quarter of the wave length, the greatest effect being produced when the plane of the coil F is at right angles to the direction of the major axis of the ellipse. The production of a rotating field is merely incidental to the so-called "goniometer" arrangement shown in Figure 2, wherein the coils D D' are at right angles and is not essential, but is an arrangement which I have found to work well in practice.

This arrangement, therefore, can be used as a direction finder, irrespective of its utility as a static interference eliminator, since the direction of origin can be located by observing the angular position of the coil F, required to give maximum signal strength. From the known separation of the antennæ, the observed wave length and the position of the coil F for maximum signal, the direction of transmission of the received signal can be calculated, as will be understood by those skilled in the art.

Referring again to Figure 1 of the drawing, the coil F is connected through suitable loading inductances G, condenser H, and coupling coil I, to the detector. In the arrangement shown, this circuit F, G, H, I, is tuned to the frequency of the incoming signal.

The detector, shown as a three element vacuum valve M, is connected to the oscillatory circuit J K coupled to coil I. The particular character of the detector or its special circuits, is immaterial and will vary with the character and strength of the signal. That shown, merely for purposes of illustration, is the circuit of my pending application No. 834,305, filed April 25, 1914, and involves in addition to the usual plate circuit P Q R S, an oscillatory circuit P U W S. Such a detector arrangement may be employed for the reception of either damped or undamped signal waves.

In operation it is desirable, and, in cases of heavy static, is sometimes essential, that the antennæ be substantially alike in wave length and decrement, and further, that the constants should be so related as to bring the currents flowing in the antennæ into substantially exact phase, i. e., that the distribution of current in the several antennæ should be substantially alike. The variable inductances C C' and condensers E are provided in order that the desired adjustments may readily be made. In the adjustment of the antennæ it will be found that it is usually not enough to adjust merely to the same wave length; indeed, such adjustment may in some instances produce little apparent reduction of static, but by varying the ratio of the constants and coupling, while substantially preserving the wave length, the static noises will often disappear or be greatly reduced, as the result of a com-

paratively slight change of adjustment. The range of adjustment for best results is narrow, but once found it is stable, requiring little or no manipulation to preserve it.

5 While the use of variable elements, in each antenna, for varying both inductance and capacity is not essential, it is convenient and is the arrangement which I prefer.

10 The use of an intermediate circuit, as here shown, is not essential, as any other arrangement suitable for the purpose may be used, but such intermediate circuit may advantageously be employed. Neither is it essential that the particular arrangement for 15 combining the circuits of the two antennæ here shown be employed, as any means which will permit the combination of the signal effects to produce either a stationary or a rotating resultant effect, while enabling the 20 effects due to static to be opposed, may be used.

Referring now to the modified arrangement shown in Figure 2, it will be seen that in this modification I employ a different 25 antenna construction, a different mode of associating the adjusting devices, and additional means for reducing static interference, which gives an important improvement in the result.

30 The antennæ *a a'* are in this instance composed each of a plurality of turns of wire insulated from one another and supported in an approximately vertical position in any suitable manner. The operation of such 35 antennæ is not different from that already described, except that larger electromotive forces will be generated owing to the increased number of turns if of the same dimensions, or a smaller loop may be used 40 to obtain a sufficient electromotive force.

The mode of connecting the adjusting devices *C C'* and *E E'* is different from that shown in Figure 1, in that coils *C C'* in this 45 instance are preferably large so as to be always nearly equal to the total inductance of the loop antennæ, and the condensers *E E'* are connected across instead of in series with the loops constituting the antennæ. This mode of connection is particularly 50 advantageous where the leading-in wires are long, or when receiving shorter wave lengths than normal.

The arrangement of adjusting means shown in Figure 2 is in effect a division of 55 the total inductance of the antenna circuit into two approximately equal inductances in parallel, thereby reducing the total inductance to one-half that of the antenna alone, and the addition of the capacity of the condenser *E* as a capacity in parallel to the capacity of the leads. If these leads are 60 long, their capacity to one another is considerable, and in the arrangement of Figure 1 this is objectionable, and the leads should 65 not be too close together. With the arrange-

ment of Figure 2 this capacity is not objectionable so long as the total capacity of the antenna circuit is not too great to permit of a sufficient range of adjustment in condenser *E*.

70 Either form of antenna may be used with either arrangement of adjusting devices.

The arrangements thus far described give a substantial freedom from static interference due to the "hissing" or "sizzling" variety 75 which I have generally found to be most prevalent and troublesome. When the "explosive" variety is present, however, there is sometimes a sufficient residue, even with the most careful adjustment, to make good reception difficult.

80 My tests seem to indicate that this residue is not due, or at least not largely due, to horizontal components in the static waves or to harmonic oscillation in the antennæ, but 85 rather to the natural coupling between the two antennæ. Proceeding on this assumption, I have found that by eliminating or reducing the natural coupling between the antennæ, I am able to obtain substantially 90 perfect elimination, even of this explosive type of static disturbance. One means of accomplishing this is shown in Figure 2, where *X X'* are two coils so arranged in 95 inductive relation to one another as to give a coupling effect between the two antennæ circuits substantially equal and opposite to the natural coupling between the two loops. So far my tests indicate that the leads of the 100 two antennæ, if arranged as above described, do not introduce any appreciable disturbance, and by cancelling out the natural coupling between the loops, by reverse coupling means such as the two coils *X X'* I am able 105 to get rid of the ordinary forms of static interference with substantial completeness.

110 In this connection I have found the goniometer arrangement herein described of especial usefulness, which I attribute to the fact that the coils *D D'* thereof are at right angles to one another, and hence do not directly affect the coupling of the two antennæ 115 circuits to one another. Since their coupling to the coil *F* can, and should be made comparatively loose, the coupling between the two antennæ, resulting from the mutual 120 relation of the coil *F*, can also be kept small; the coils *X X'* can therefore be used to effect a substantially complete balancing out of the coupling between the loop antennæ. I 125 believe the use of a goniometer, in a system of this kind, to be original with me and it was first described by me in an application Serial No. 157,594, of which this application is a continuation in part.

130 It will be understood that coils *X X'* are in no way dependent upon association with the particular multiple loop antennæ with which they happen to be shown in my drawing, but are available without reference to

the particular antenna construction employed.

My invention is in no way limited to the use of two antennæ only, nor is it essential that these be strictly vertical, as I have used loop antennæ inclined at an angle as great as forty-five degrees from the vertical, with excellent results. Also it is not essential that the several antennæ should be of identical dimensions nor is it essential that they should be of the same type, although I have so far found these the preferable conditions. Variations in the above and other respects, may be made without departing from the scope of my invention.

While I have herein specifically illustrated and described only loop antennæ, I do not regard my invention as necessarily limited thereto, and it will be understood that even the ordinary open form with earth connection may be substituted, but for best effect in such a case, direct connected leads should be avoided, or so arranged as to be affected as little as possible by the incoming signal, as otherwise the actual separation of the antennæ is not the effective separation. In such a case also, the provision and careful use of phase adjusting means is of special importance.

I have shown and described my invention in the best form now known to me, but I contemplate as within its scope all modifications and equivalents whether now known or subsequently discovered, which do not depart from the essential principle of the invention, and which utilize the discoveries I have made and herein disclosed. I regard as within my invention, and claim broadly, any means for discriminating between waves or impulses which travel vertically or appear to have a predominant vertical component and signal waves which are assumed to be waves travelling in a substantially horizontal direction and eliminating the first, while detecting the second.

In using in my claims the word "differentially", I intend to designate such a combination of the effects due to static or other interference, as tends to a zero or minimum effect on the detector, whether through the use of one or more local circuits or not, and, similarly, I use the word "cumulatively" as designating such a combination of the effects due to the desired energy, as tends to produce an effect upon the detector. By the term "heterogeneous" in my claims, I intend to designate disturbances which do not exhibit definite wave length, but cause oscillations of the frequency of the antenna.

In referring to portions of the receiving system as differently "circumstanced", I mean to include either position or adjustment of the antennæ, or both position and adjustment.

In describing in the claims static as being

vertically or non-horizontally propagated, it will be understood that I do not wish to be limited by any theory of the origin, direction, or wave-like character of static, but intend to designate those disturbances which, in the circuits described, act in some respects like vertically propagated waves. In describing in the claims the combining or opposing of currents, I intend to include any effect or accompaniment of such currents, as, for example, magnetic fields or electromotive forces.

In further explanation of the mode of operation of the improved apparatus described herein, attention is called to the fact that when the separation of the collectors or loops is an appreciable fraction of a wave length in the line of transmission as above described, the signal current when at a maximum in one collector has a reduced or negative value in the other collector and, therefore, the collectors operate to give different ratios of instantaneous values of static current and signal current, and it is because of this different instantaneous ratio or unbalanced condition that I am enabled to balance out the static and retain the signal. In my pending application, Serial No. 244,564, I have described other means for producing this difference of ratio or unbalanced condition which, however, make use of this same general principle or mode of operation, and I have pointed out in my said application that this different instantaneous ratio may be obtained independent of the different phase relation of the signal currents in the two collectors, that is to say may be obtained by so constructing, circumstancing, or disposing the collectors with respect to each other, that they inherently have a different ratio.

Having now described my invention, what I claim is:

1. In apparatus of the kind described, a plurality of antennæ separated by an appreciable fraction of a wave length and connected to coupling coils disposed in non-inductive relation to each other and a receiving circuit comprising a coupling coil in inductive relation to both of the first mentioned coils.

2. In apparatus of the kind described, a plurality of antennæ separated by an appreciable fraction of a wave length and connected to coupling coils disposed in non-inductive relation to each other, and a receiver circuit comprising an adjustable coupling coil disposed in inductive relation to each of the first-named coils.

3. In apparatus of the kind described, a plurality of antennæ located at unequal distances from the source of signals to be received, a receiving circuit comprising a rotatable coupling coil, a plurality of coils connected to the antennæ and associated

with the coupling coil in such manner that currents flowing simultaneously in the coils will produce opposing effects in the coupling coil.

5. The improvement in the art of radio reception which consists in reducing the static interference at a collecting station by receiving disturbances acting as though propagated in a vertical direction and those 10 propagated in a horizontal direction as currents of the same frequency but of different relative phase, and eliminating the first while detecting the last-named disturbances.

5. The improvement in the art of radio 15 transmission, which consists in receiving waves due to static reaching different portions of a receiving system substantially simultaneously, and waves of definite period arriving successively as currents of the same 20 frequency, utilizing the relative time of arrival to discriminate between them and detecting the last-named waves.

6. The improvement in the art of radio 25 transmission, which consists in discriminating between waves due to static affecting different portions of a receiving system substantially simultaneously and waves of definite period affecting these successively by combining differentially the simultaneous 30 effects, and combining cumulatively those which are successive and detecting the last-named effects.

7. The method of reducing interference 35 in radio transmission, which consists in combining in one receiving device the effects produced by static disturbances received simultaneously and definite wave length disturbances arriving at different times in a plurality of separated antennæ, and utilizing 40 the relative time of arrival to discriminate between them by causing said device to respond more readily to disturbances of definite wave length, reaching said antennæ successively than to static disturbances 45 reaching them more nearly simultaneously.

8. The method of reducing interference in 50 radio transmission due to static disturbances, which consists in differentiating between waves received from vertical and horizontal directions by causing horizontal waves of the desired signal to produce electro-motive 55 forces in a plurality of receiving collectors having one order of phase difference, and causing those from a vertical direction to produce electro-motive forces having a 60 phase difference of a lesser order, combining differentially the effects of lesser order of phase difference, combining cumulatively those of the greater order, and utilizing said 65 last-named effects.

9. The method of reducing the effect of 70 static disturbances, which consists in locating and adjusting a plurality of antennæ and associated circuits in such manner that 75 static effects will produce therein currents

similar in phase and signal impulses will produce therein currents dissimilar in phase, combining differentially said currents similar in phase, and combining cumulatively 80 said currents dissimilar in phase, and detecting the presence of said last-named currents. 70

10. The method of reducing the effect of 85 static disturbances in radio transmission, which consists in so relatively adjusting 75 each of a plurality of antenna circuits as to cause currents of unlike phase to be set up therein by signals received in one direction in a horizontal plane, and to cause currents of similar phase to be set up by disturbances propagated in a vertical direction 90 at right angles thereto, producing a resultant magnetic field having one direction by said in-phase currents, and a magnetic field having a maximum effect in a different direction by said out-of-phase currents, and subjecting a receiving circuit to said fields so as to selectively receive energy from a 95 desired one of said fields. 90

11. The method of reducing static interference in radio reception, which consists in arranging a plurality of antennæ to have a directional action for horizontally received waves in a definite direction, receiving the static interference and the desired 100 waves in such antennæ, adjusting the circuit constants thereof to cause static waves, to produce in said antennæ currents of the same phase, determining the separation of 105 said antennæ so as to cause horizontally received signal waves from the desired direction to produce currents having phase difference of a greater order, combining the former differentially and the latter cumulatively in a common receiving device, and detecting the last-named currents. 105

12. The method of reducing static interference in radio reception, which consists in causing the received signal to produce out of phase currents in a plurality of collectors, 110 causing heterogeneous disturbances to produce currents having a different relative phase, and selectively rejecting the last-named effects by the aid of said distinction 115 in phase difference. 110

13. The improved method of radio reception, which consists in intercepting the signal waves at two points disposed at unequal 120 distances from the source of the waves, thereby obtaining signal oscillations out of phase with each other, combining the effect of these to produce signals, and combining the oscillations set up at the two points by static, in phase, to neutralize each other, substantially as described. 120

14. The method of reducing the interference 125 in radio transmission, which consists in discriminating between highly damped heterogeneous waves, due to static disturbances and less strongly damped signal waves of 130

- definite period, by subjecting a plurality of antennæ to the effects of both the heterogeneous waves and the received signal waves, and adjusting the constants of the antennæ so as to cause the electro-motive forces induced therein by the static disturbances to set up currents in said antennæ of substantially the same frequency, joining the effects in said antennæ in a common circuit where-
 10 by said static currents are opposed and their effects minimized while signal currents are combined and retained.
15. The method of reducing the interference with radio communication, due to atmospheric disturbances which do not behave as though possessed of either definite wave length or decrement, which consists in circumstancing a plurality of antennæ so as to cause the electro-motive forces induced therein by atmospheric disturbances to set up currents of substantially the same wave length and decrement, and to cause signal waves to set up currents of the same wave length but relatively different phase, and
 20 opposing the currents due to atmospheric disturbances in a receiver circuit to obtain substantial neutralization of said currents, while retaining the currents due to signals having definite wave length.
- 25 16. The method of reducing the interference with radio communication, due to atmospheric disturbances which do not behave as though possessed of either definite wave length or decrement, which consists in positioning and adjusting a plurality of antennæ so as to cause the electro-motive forces induced therein by atmospheric disturbances to set up currents of substantially the same wave length and decrement, and to cause signal waves to set up currents of the same wave length but relatively different phase, and opposing the currents due to atmospheric disturbances in a receiver circuit to obtain substantial neutralization of said currents, while retaining the currents due to signals having definite wave length.
- 30 17. In radio signalling the method of distinguishing between impulsive disturbances, such as static, and impulses having definite wave length and small decrement, which consists in receiving both in a plurality of antennæ which are all of the same frequency, and adjusting the relative phases of the currents produced in the circuits to minimize the effect of said impulsive disturbances.
- 35 18. The method of reducing static disturbances in radio signalling, which consists in receiving both static and signal im-
 40 pulses in a plurality of antennæ as a plurality of currents of the same frequency but relatively different phase, and selecting the desired current by discriminating between the phases thereof.
- 45 19. The method of reducing static interfer-
 ence in radio reception, which consists in receiving static and signal waves in a plurality of antennæ, disposed in a plane in-
 50 cluding the station transmitting the desired signals, and combining the currents set up in said antennæ to produce in a receiver circuit effects having a ratio of static and signal currents differing from that existing in the individual antennæ.
20. The method of reducing the interference with radio communication due to static disturbances, which consists in causing the static impulses and signal waves to set up currents having the same frequency in a plurality of antennæ, adjusting the phases of said currents, and combining them in a common receiving circuit, whereby the ratio between the signal currents and static currents in the common receiving circuit, is greater than the ratio existing between said currents.
- 25 21. The method of reducing the interference with radio communication due to static disturbances, which consists in causing the static impulses and signal waves to set up currents having the same frequency but of relatively different phase in a plurality of antennæ, and combining the effects of said currents in a common receiving circuit in such phase relation that the ratio between the signal currents and static currents is greater than the ratio existing between said currents in the individual antennæ.
- 30 22. At a radio transmission receiving station, a plurality of antennæ effectively separated from one another by an appreciable fraction of a wave length in the direction of desired reception, and means associated with said antenna circuits for controlling the relative phases of effects produced by static disturbances in said antennæ.
- 35 23. At a radio transmission receiving station, a plurality of antennæ effectively separated from one another by an appreciable fraction of a wave length in the direction of desired reception, means associated with said antennæ for definitely controlling the relative decrement and phase of effects produced by static disturbances received in said antennæ, and a receiving device common to said antennæ.
- 40 24. At a radio transmission receiving station, a plurality of antennæ effectively separated from one another by an appreciable fraction of a wave length in the direction of desired reception, a common receiving device, connections therefrom to each of said antennæ, and means for definitely controlling the relative decrement and phase of oscillations set up in said receiving device by static disturbances in said antennæ.
- 45 25. At a radio transmission receiving station, a plurality of antennæ separated from one another by an appreciable fraction of a wave length in the direction of desired re-

- ception, a common receiving device, connections therefrom to said antennæ, and means for bringing into accord the time periods, decrement and phase of natural oscillations in said antennæ, produced by static disturbances, a detecting means, and means for selectively influencing said detecting means by effects produced in said antennæ.
26. Means for reducing the effect of static disturbances, which comprise a plurality of antennæ located at suitable distances apart horizontally in a direction to be effected successively by signal impulses, to produce therein currents dissimilar in phase, means for adjusting the antenna circuits so that static effects will produce therein currents similar in phase, means for combining differentially said currents similar in phase, means for combining cumulatively the currents dissimilar in phase, due to the signal impulses, and means for detecting the presence of said last-named currents.
27. At a receiving station, in a radio transmission system, a plurality of antennæ separated in the line of desired communication and adjusted to be differently affected by heterogeneous disturbances and signals received from said desired direction, at least one of which antennæ is constructed to be directive for best reception in said direction, connections therefrom to a common receiving device, and means for distinguishing between said effects.
28. At a receiving station, in a radio transmission system, a plurality of separate antennæ arranged to be differently affected by static disturbances and signals received from a desired direction, connections therefrom to a common receiving device and a local circuit in said receiving device, and means for differentially affecting said circuit by said static disturbances and cumulatively affecting it by signals from the desired direction.
29. At a radio transmission receiving station, a plurality of directive antennæ, the plane of each antenna being parallel to a given plane and the antenna being separated an appreciable fraction of a wave length in the direction of desired reception.
30. At a radio transmission receiving station, a plurality of loop antennæ separated a considerable fraction of a wave length in the direction of desired reception, the plane of each loop being parallel to a given plane, a receiving device, and leads therefrom to said antennæ.
31. At a radio transmission receiving station, a plurality of loop antennæ separated a considerable fraction of a wave length in the direction of desired reception, the plane of each loop being parallel to a given plane, a receiving device and leads therefrom to said antennæ, the leads from each antenna being similarly located with respect to earth.
32. At a radio transmission receiving station, a plurality of loop antennæ arranged in a common plane and separated by an appreciable fraction of a wave length to be received whereby currents of different phase are produced in said antennæ, the plane of each loop being parallel to said plane, a receiving device, and means for adjusting at least one of said antennæ.
33. At a radio transmission receiving station, a plurality of loop antennæ arranged in a common plane, the plane of each loop being parallel to said plane, and separated a considerable fraction of a wave length to produce currents of different phase in said antennæ, a receiving device, and means for adjusting at least one of said antennæ.
34. At a radio transmission receiving station, a plurality of separated loop antennæ, a receiving device, means for adjusting at least one of said antennæ, a detecting device, and means for differentially affecting said device by received energy due to heterogeneous disturbances and for cumulatively affecting it by energy propagated in a definite direction.
35. At a radio transmission receiving station, a plurality of separated loop antennæ, a receiving device, leads therefrom to said antennæ, and means for adjusting at least one of said antennæ, said means comprising a plurality of adjusting devices symmetrically located in said leads.
36. A radio receiving station, a plurality of separate antennæ disposed at different distances from the transmitting station, so that the oscillations set up therein by the signal waves will be out of phase, means for adjusting the constants of the antenna circuits so that oscillations set up therein by static will be in phase, means for combining out of phase signal oscillations to produce signals, and means whereby the in-phase oscillations are made to act on the receiving apparatus in an opposite manner so as to negative each other.
37. At a radio receiving station, a plurality of separate antennæ arranged in a common plane and connected to a common receiving device, and means for neutralizing the natural coupling of the two antennæ.
38. At a radio receiving station, a plurality of separate loop antennæ arranged in a common plane and connected to a common receiving device, and means for neutralizing the natural coupling of the two antennæ.
39. At a radio receiving station, a plurality of separate loop antennæ separated in the line of desired communication, and coupled to a common receiving device, and means for neutralizing the natural coupling between said antennæ.
40. At a radio transmission receiving sta-

tion, receiving apparatus, a loop antenna separated therefrom at a distance, and a plurality of leads electrically connecting the antenna and the receiving apparatus, said 5 leads being relatively arranged to minimize picking up static.

41. In an apparatus of the kind described, a pair of directional antennæ effectively separated by an appreciable fraction of a 10 wave length in the direction of desired reception, rotary field producing means associated with said antennæ, and a receiver associated with said means.

42. In an apparatus of the kind described, 15 a pair of directional antennæ effectively separated by an appreciable fraction of a wave length in the direction of desired reception, each antenna being directional in said direction, rotary field producing means 20 associated with said antennæ, a local circuit associated with said means, and receiving devices associated with said circuit.

43. In an apparatus of the kind described, 25 a pair of loop antennæ arranged in a common place and effectively separated by an appreciable fraction of a wave length, leads therefrom to a common point arranged to have minimum receptive effect for static, coupling coils connected to said leads disposed in non-inductive relation to each 30 other, and a receiving circuit comprising

a coupling coil in inductive relation to both of the first mentioned coils.

44. A radio receiving system comprising 35 in combination a plurality of collectors spaced apart a material fraction of a wave length in the direction of signal reception, a common indicating means, and means whereby the action of the static on the several collectors simultaneously is neutralized 40 leaving the current due to signal unneutralized.

45. The method of reducing the effects of static in radio reception comprising setting 45 up a plurality of signal currents of the same frequency, but whose maxima occur at different instants of time, setting up a plurality of static currents of the same frequency and whose maxima occur the same instants of time, neutralizing said static currents, and indicating said signal currents. 50

46. In a radio receiving system, in combination, a plurality of collectors free from tuning to different wave lengths adapted to give different ratios of instantaneous values 55 of static current and signal current therein, the system having a material horizontal exposure, and means whereby the current due to static impinging on different parts of the system substantially neutralizes leaving the 60 current due to signal unneutralized.
